UNITED STATES PATENT OFFICE

GUSTAV TER MEER, OF MUNICH, GERMANY, ASSIGNOR TO ALBERT T. OTTO & SONS, OF NEW YORK, N. Y., A CORPORATION OF NEW YORK

CENTRIFUGAL MACHINE

Application filed September 23, 1931, Serial No. 584,802, and in Germany January 10, 1930.

I have filed applications in Germany on January 10, 1930, and September 16, 1930.

This invention relates to continuously working centrifugal machines with imperforated drum, in which solid materials are separated from liquids or semi-liquid materials under the action of the centrifugal force, wherein such materials are admitted into the drum continuously or periodically. The solid materials are thereby deposited on the circumferential walls of the drum, while the specifically lighter clarified liquid runs off over the edge of the open side of the drum during the admission of fresh material to be treated. The efficiency of the known centrifugal machines of this type has not given satisfaction, because the liquid, which runs quite clarified from the drum at the beginning of the operations gradually becomes more and more clouded through particles of solids, which are carried away with the liquid. Careful study has revealed, that the cause of the insufficient separation must be looked for in the fact that a loosening of the solid substances already deposited on the wall of the drum takes place, which is caused by the newly introduced material to be treated. The said newly introduced material is thrown with great velocity and force in a vertical direction on the deposited solid substances and thus stirs these solid materials up again. Strong eddies are created at these spots, through which the solid particles are torn away in the direction of flow, so that they leave the drum together with the liquid.

The main object of the present invention is to eliminate this fault. This is attained in accordance with this invention in the manner, that the material to be treated, which enters the drum and tends to flow in the direction of the circumferential wall of the drum under the influence of centrifugal force, is deflected in its flow into a direction at least nearly parallel to the circumferential wall of the drum by suitable means and within the zone of solid particles.

The efficiency of the centrifugal machine can further be improved by careful distribution of the material under treatment within the drum. According to the present inven-

tion this is done by an annular distributor pipe within the drum, such pipe having a slot along its whole length, which may preferably be made adjustable.

Further objects and advantages of the invention will become apparent as the description proceeds.

In the accompanying drawings:

Fig. 1 is a longitudinal section through a centrifugal machine,

Fig. 2 is a cross section along the two lines A—B and C—D,

Fig. 3 is a special design of the drum.

1 is the continuously revolving shaft of the centrifugal machine which is supported in two bearings 2 and 3. It carries on one end the driving pulley 4. The drum 5 is rigidly wedged on the shaft 1 between the two bearings 2 and 3. The drum is surrounded by a casing, consisting of the upper portion 6 and the lower portion 7. On the inside of the drum and at some distance from the back wall of the drum an annular wall 8 is provided, vertically to the shaft 1. The said wall 8 is connected with the back wall of the drum by means of radial ribs 9, the innermost end of which is bent off tangentially as shown on Fig. 2, thus forming radial conduits 12 for the material under treatment. The latter is introduced into the drum through the pipe 13, which ends in an annular channel 14 of the distributor pipe 15. The latter is fastened to the discharge spout 17 by means of the annular bracket 16. The annular distributor pipe is provided with a slot 18, extending all over its length and pointing towards the back wall of the drum and having a slide 19, which enables a variation of its width, so that it can be adjusted to the nature of the material to be treated.

The material under treatment leaves the distributor pipe 15 on its whole circumference in an even flow and enters the conduit channels 12 of the drum. The centrifugal force throws it at first radially towards the circumferential wall of the drum, but within the zone 20, in which the solid particles are deposited on the circumferential wall of the drum an annular slit 21 is provided, which is formed on the one side by the outer edge of

the annular wall 8 and on the other part by the ring 22 opposite the former. This slit alters the radial flow of the material under treatment by deflecting it, so that the flow 5 has now a direction practically parallel with the circumferential wall of the drum. In this manner a vertical throw of the material against the layer of solids 20 on the wall of the drum and thus the disturbance of the 10 latter solids is avoided. The liquid is thus separated during its flow towards the edge of the drum from the heavier solid particles through the action of the centrifugal force, whereby the solid particles come to rest in 15 the layer 20 as they leave the annular slit 21. The clarified liquid leaves the drum over the edge 23.

The ring 22 may preferentially be hollowed on the edge opposite the annular wall 8, thus deflecting the material passing into 20 centrifuging zone of the drum 5 in a gentle curve.

As shown on Fig. 1 the ring 22 will be made of such dimensions, that its inner diameter 25 will come level with the inner limit of the zone 20 of the solid materials.

The invention may be worked also in a manner as shown on Fig. 3. In this the circumferential wall of the drum is provided 30 with a shoulder to take the place of the ring 22. The provision of the ring 22 is however preferable owing to the greater simplicity and every imperforated drum of a centrifugal machine can thus be altered in accordance 35 with the present invention.

Having thus described my invention, what I claim as new and desire to secure by Letters Patent is:

1. A centrifugal machine for separating 40 solids from liquids, including a rotary drum having an imperforate peripheral wall, an annular series of radially extending conduits for delivering the material to be treated towards the periphery of said drum, and an 45 annular nozzle at the outer ends of said conduits for projecting the material in a direction substantially parallel to the axis of rotation of the drum.

2. A centrifugal machine for separating 50 solids from liquids, including a rotary drum having an imperforate peripheral wall and an end wall, an annular member spaced from said end wall and forming therewith a passage for the delivery of material to be treated 55 ed, towards the periphery of said drum, and a ring encircling the discharge end of said passage and forming with said wall member an annular slot concentric with said peripheral wall and adjacent thereto, and facing in 60 a direction substantially parallel to the axis of rotation of said drum.

3. A centrifugal machine for separating 65 solids from liquids, including a rotary drum having a peripheral wall and an end wall, an annular partition spaced from said end

wall, and a plurality of ribs connecting said wall member to said end wall, and forming a series of radially extending passages, the radially inner ends of said ribs being offset in a tangential direction.

4. A centrifugal machine for separating solids from liquids, including a rotary drum having an imperforate peripheral wall and an end wall, a partition spaced from and approximately parallel to said end wall, a plurality of ribs connecting said partition and said end wall, and forming therewith an annular series of substantially radially extending channels terminating adjacent to said peripheral wall, a ring encircling the radially outer ends of said channels and spaced therefrom to form nozzles for deflecting material towards the end of the drum opposite to said end wall, an annular conduit concentric with respect to said peripheral wall, and having an annular discharge nozzle near the radially inner ends of said channels, and a conduit for delivering material to be treated to said annular conduit.

5. A centrifugal machine for separating solids from liquids, including a drum adapted to be rotated about a horizontal axis and having an imperforate peripheral wall and an end wall, a partition in said drum spaced from and substantially parallel to said end wall, and forming therewith a passage for substantially radial flow of material to be treated, said peripheral wall having an annular portion offset inwardly at the end thereof near said end wall to form a shoulder spaced from the radially outer end of said passage for directing the liquid from said passage towards the end of said drum opposite to said end wall and in a path spaced inwardly from said peripheral wall.

6. A centrifugal separator including a drum rotatable about a horizontal axis, and having an imperforate peripheral wall and an end wall, a non-rotatable annular delivery member disposed within the drum adjacent to the end wall, and having an annular outlet concentric with said peripheral wall adjacent to and encircling the axis of the drum, and means coacting with said end wall to form a passage for receiving material from said annular outlet and conducting it in all directions radially of the drum, while preventing circumferential movement of the material in respect to the drum, said passage having an annular outlet facing in a direction substantially parallel to the axis of the drum and adjacent to but spaced inwardly from said peripheral wall.

7. A centrifugal machine for separating solids from liquids, including a drum rotatable about a horizontal axis and having an imperforate peripheral wall and an end wall, a wall member in said drum and spaced from said end wall to form therewith a pas-

sage for conducting in a radial direction the material to be treated, and an annular ring within said peripheral wall and forming with said wall member an annular slot concentric with said peripheral wall but spaced therefrom, said ring having the radially inner side thereof curved to direct the material toward the end of the drum opposite to said end wall.

10 8. A centrifugal separator, including a separating drum rotatable about a horizontal axis and having a peripheral wall and an end wall, a stationary annular conduit encircling the axis of said drum and disposed 15 adjacent to said end wall and having an annular outlet, an annular slide member engaging said conduit and also encircling the axis of said drum and movable axially of said drum for controlling said outlet, and 20 means for directing material from said outlet toward said peripheral wall and thence substantially axially in a path spaced inwardly from said peripheral wall.

In testimony whereof, I have signed my 25 name to this specification.

GUSTAV TER MEER.
